UNITED STATES PATENT OFFICE.

HERMAN ABRAMS, OF PHILADELPHIA, PENNSYLVANIA, ASSIGNOR TO CRESCENT
BRASS MFG. CO., OF READING, PENNSYLVANIA, A CORPORATION OF PENNSYLVANIA.

DESIGN FOR A PLATE FOR LIGHTING FIXTURES.

Application filed January 8, 1926. Serial No. 16,004. Term of patent 7 years.

To all whom it may concern:

Be it known that I, HERMAN ABRAMS, a citizen of the United States, residing at Philadelphia, in the county of Philadelphia and State of Pennsylvania, have invented a new, original, and ornamental Design for a Plate for Lighting Fixtures, of which the following is a specification, reference being had to the accompanying drawing, forming part thereof.

Fig. 1 is a side elevation showing my new design.

Fig. 2 is a bottom view, two of the arms

and a portion of the center being shown in full lines, with ornamentation complete, the other three arms and the remainder of the center being indicated by dotted lines with the surface ornamentation omitted, it being understood that such ornamentation is repeated upon each of the arms and throughout the center.

I claim,

The ornamental design for a plate for lighting fixtures, as shown.

HERMAN ABRAMS.
